(57) **CLAIM**

I claim the ornamental design for a display package, as shown and described.

DESCRIPTION

FIG. 1 is a perspective view of a display package showing my new design;

FIG. 2 is a front elevational view of the display package shown in FIG. 1;

FIG. 3 is a top view of the display package shown in FIG. 1;

FIG. 4 is a view of the display package taken from the left side of FIG. 1;

FIG. 5 is a view of the display package taken from the right side of FIG. 1;

FIG. 6 is a bottom view of the display package shown in FIG. 1;

FIG. 7 is a rear view of the display package shown in FIG. 1;

FIG. 8 is a cross-sectional view of the display package taken on line 8—8 of FIG. 7;

FIG. 9 is a cross-sectional view of the display package taken on line 9—9 of FIG. 7; and,

FIG. 10 is an enlarged detail view of the display package taken on line 10—10 of FIG. 8.

The broken line showing of the packaged product is for illustrative purpose only and forms no part of the claimed design.
